UNITED STATES PATENT OFFICE

WILLIAM A. HANSES, OF CHICAGO, ILLINOIS, ASSIGNOR TO RAND McNALLY & COMPANY,
OF CHICAGO, ILLINOIS, A CORPORATION OF ILLINOIS

DISPLAY SHEET RACK

Application filed May 31, 1930. Serial No. 458,493.

My invention relates to racks for supporting display sheets such as, and more particularly, maps wound upon spring rollers and commonly used in educational institutions.

5 One of my objects is to provide a rack of simple, relatively inexpensive, and durable construction for removably supporting therein a plurality of frames on which the rollers carrying the display sheets are journaled, 10 the display sheets being adapted for selective unwinding from the rollers for exhibition purposes while in the rack and the several frames being removable therefrom for individual positioning at any location at 15 which the display sheet is to be exhibited.

Such an arrangement makes for great economy in the equipping of schools with display sheets such as maps or the like, inasmuch as the display sheets may be stored in 20 the rack for display therein at one location and the individual display-sheet-supporting frames may be removed therefrom and used at any desirable location, such an arrangement being especially advantageous to communities where the cost of providing each 25 room with the same set of display sheets, would be prohibitive.

Another object is to provide a novel, simple, inexpensive, and durable construction 30 of frame in which the display-sheet-supporting roller is journaled; and other objects as will be manifest from the following description.

Referring to the accompanying drawing: 35 Figure 1 is a view in front elevation of a rack constructed in accordance with my invention and shown as housing one of a plurality of display-sheet-supporting frames adapted to be housed within the rack.

40 Figure 2 is a plan view of one of the similar frames referred to.

Figure 3 is an end view of the frame of Fig. 2, the structure being viewed from the right-hand side of this figure.

45 Figure 4 is a broken enlarged view of the

right-hand end of the structure in Fig. 1.

Figure 5 is an enlarged section taken at the line 5—5 on Fig. 1 and viewed in the direction of the arrows; and

Figure 6, an enlarged broken sectional view taken at the line 6—6 on Fig. 1 and viewed in the direction of the arrows.

Referring to the rack construction shown, it comprises a frame 7 shown as formed of an upper member 8, a lower member 9 and end members 10 and 11. These members, which preferably are formed of wood, may be secured together in any desirable way as for example by setting the upper and lower ends of the members 10 and 11 into gains 12 and 13 in the members 8 and 9, respectively, these parts being held together by screws (not shown) or any other suitable fastening devices, extending through the members 8 and 9 and into the members 10 and 11.

The frame 7 at its opposite ends is provided with vertical series of ledges 14 and 15, respectively, adapted for the supporting of a vertical series of horizontally extending display-sheet-supporting frames of the same 70 construction, one thereof being represented at 16 and hereinafter described.

The ledges 14 are shown as formed of tongues cut from the metal of a strip 17 of angular shape in cross section presenting a plate portion 18 extending substantially parallel with the front face of the rack, a forwardly projecting flange 19 at which the member 17 fits flatwise against the inner surface of the cross member 11 and to which it is secured, as for example by the screws represented at 20, and a rearwardly extending flange 21 at its opposite edge from the metal of which the ledge-forming tongues 14 are cut, these tongues being bent to extend into substantially horizontal position as shown.

The distance between adjacent ones of the ledges 14 is considerably greater than the height of the frames 16 and to prevent shifting of the racks in the plane of the members

17, other tongues represented at 22 are cut from the flange 21 of the member 17, the frames 16 fitting fairly snugly in between the ledges 14 and the adjacent ones of the tongue 22.

5 The member 17 is also provided with means adapted to be moved into and out of a position lapping the front surfaces of the frames 16, these means being shown as in the form of levers 23 pivotally mounted, as indicated at 24 on the plate portion 18 of the member 17.

10 The ledges 15 in the particular construction shown are formed of tongues bent rearwardly from the metal of a flange portion 25 of a plate member 26 which fits flatwise against the inner surface of the cross member 10 and is secured thereto, as for example by the screws represented at 27, other tongues 28 being formed from the metal of the flange 25 and corresponding with, and functioning 15 in the same way as, the tongues 22.

15 The ledges 15 thus provided are set back inwardly of the free edge of the flange 25 whereby portions of the latter and represented at 29 extend in such a position that when the frames 16 are positioned in the rack, these portions 29 will form abutments preventing forward displacement of the frames 20 16 at their left-hand ends in Fig. 1.

25 It may be here stated that the rack 7 to the rear of the portions 29 and in spaced relation thereto is provided with a rear abutment 30 which may be in the form of a wooden board preferably secured to the inner side of the cross member 10 and of substantially the same height as the member 25—26, the frames 16 at their left-hand ends fitting between the plate portions 29 and the abutment 30. The opposite end of the rack 7 is provided with a similar abutment represented at 31 for the right-hand ends of the frames 16 which latter, when positioned in the rack and the levers 20 33 are swung to a position for lapping the frames 16, extend between these levers and the abutment 31 as shown in Fig. 6.

40 Referring now to the particular illustrated construction of frames 16, it comprises a rear bar 32 shown as formed of sheet metal bent into the cross sectional shape represented in Fig. 3 whereby this member is in the form of a hollow bar open at its rear side throughout its length as represented at 33. The frame also comprises end pieces 34 shown as in the form of metal plates 35 the metal at the edges of these plates being bent over to form flanges 36, 37, 38 and 39, the members 34 being secured to the front faces of the members 32 by screw bolts 40 extending through the flanges 37 and the front wall portions of the members 32. The flange 39 is formed with an extension 41 at its upper end which curves upwardly and outwardly beyond the plate 35, these two flange extensions 41 at the opposite ends of the frame 16 forming stops in position 45 to be engaged by the ends of the binding bar,

or stiffening strip, represented at 42 and commonly provided along the lower edge of the roller mounted display sheet represented at 43, the ends of the member 42 extending beyond the lateral edges of the sheet 43 and in a position to engage the stop flanges 41 under the action of the spring roller represented at 44 on which the display sheet 43 is wound.

50 The spring roller 44 may be of any suitable construction, as for example that commonly used in constructions of this kind, one end thereof having a journaling portion 45, as for example the left-hand end in Fig. 1 which is journalled in the plate portion 35 of the adjacent end member 34 of the frame 16 and the other end having a portion 45 of angular shape in cross section which is connected with the spring of the roller and extends into an opening 46 of similar shape in the plate 35 of the adjacent end member 34, whereby upon pulling down on the bar member 42 the display sheet 43 unwinds from the roller into display position against the resiliency of the spring device of the roller.

55 The frame member 32 projects at its ends beyond the cross members 34, and in positioning the frame 16 in the rack, the left-hand end of the member 32 (Figs. 1 and 2) is inserted into the space between one of the ledges 15 and a tongue 28 immediately above the latter and between the portion 29 and the rear abutment 30. The frame is then swung at its right-hand end to become positioned between one of the tongues 14 and the tongue 22 immediately above the latter and the one of the levers 23 positioned adjacent thereto then swung to the position shown in Fig. 4 whereupon the frame 16 becomes confined between the rear stop member 31 and the lever 23 referred to, it being noted that the member 18 is provided with a series of projections 47, one for cooperation with each lever 23 to limit counter-clockwise rotation of these levers beyond the position shown of the one in Fig. 4 in lapping engagement with the frame 16.

60 It will be understood from the foregoing that the rack thus provided is adapted to receive a plurality of the frames 16 (the particular construction shown being adapted to receive four of these frames) which become disposed therein in substantially parallel horizontal position and in a series extending vertically. In the arrangement shown any one of the display sheets 43 may be unrolled for display purposes, without disturbing any of the other sheet-supporting devices in the rack, and when it is desired to use any one of the individual sheet-displaying devices at another location than at the rack, as for example in another room of a building in which 115 the rack is provided, such device may be readily removed from the rack and hung at the desired location, as for example upon hooks (not shown) projecting from a wall and adapted to be received into slots 48 pro- 120

vided in the upper surface of the bar 32 adjacent its opposite ends.

While I have illustrated and described a particular construction embodying my invention, I do not wish to be understood as intending to limit it thereto as the same may be variously modified and altered without departing from the spirit of my invention.

What I claim as new, and desire to secure by Letters Patent, is:

1. A roller-mounted display-sheet device comprising a frame formed of a rear bar member of sheet metal having its long edges bent rearwardly in opposite directions to form a bar of hollow form in cross section, brackets having end plate portions and upper, lower and rear flanges located at the ends of said hollow bar, said rear flanges flatwise opposing the front portion of said bar and being secured thereto, a roller journaled on said plate portions, and a display sheet wound on said roller.

2. A rack comprising a frame having supports for a plurality of removable and replaceable roller-mounted-display-sheet supporting frames, stop means preventing rearward displacement of said second-named frames, and pivotally mounted devices on said first-referred-to frame and extending beyond the end faces of said second-named frames and adapted to be rotated intolapping relation to said second-named frames for preventing forward displacement of the latter.

3. A rack comprising a frame, supports at its opposite ends for a plurality of removable and replaceable roller-mounted-display-sheet supporting frames comprising sheet metal members having portions thereof bent to provide ledges for supporting said second-named frames at their ends, one of said sheet metal members comprising a central portion extending substantially parallel with the plane in which the face of said first-named frame extends and portions extending in opposite directions from the vertical edges of said central portion and at angles to the face of said first-named frame, said ledges in said last-referred-to sheet metal member cut from the metal of the one of said portions which extends rearwardly from said central portion, and bent to project toward the center of said first-named frame, stop means on said first-referred-to frame for preventing rearward displacement of said second-named frames, and means on said central portion and movable into and out of a position for preventing forward displacement of said last-referred-to frames.

4. A rack comprising a frame having supports for a plurality of removable and replaceable roller-mounted display-sheet-supporting frames, stop means preventing rearward displacement of said second-named frames, stationary abutment means in front

of, and spaced from, said stop means and between which said second-named frames, at one end, extend, and stop devices at the end of said first-referred-to frame for holding said second-named frames against forward displacement, pivoted to said first-referred-to frame beyond the adjacent ends of said second-named frames and adapted to be rotated into positions in which they lap the front sides of said second-named frames.
